UNITED STATES PATENT OFFICE.

LEO WEISENBURGER, OF MOUNT VERNON, NEW YORK.

HAT-TIP.

SPECIFICATION forming part of Letters Patent No. 656,706, dated August 28, 1900.

Application filed May 4, 1900. Serial No. 15,531. (No model.)

To all whom it may concern:

Be it known that I, LEO WEISENBURGER, a subject of the Emperor of Germany, residing at Mount Vernon, in the county of Westchester and State of New York, have invented a new and useful Mirror-Holder for Hats, of which the following is a specification.

This invention relates to improvements in hat-mirrors; and the object thereof is to provide a very simple and efficient means for holding a mirror upon the inside of a hat without the necessity of using cement, screws, or similar fastening devices which mar and disfigure the appearance of the hat.

To set forth the invention fully, the preferred form thereof is described in the following specification and shown in the accompanying drawings, which form a part thereof, and in which—

Figure 1 is a bottom view of the inside of a hat, showing the invention applied thereto. Fig. 2 is a longitudinal section of the device as applied to the hat. Fig. 3 is an enlarged cross-section of the device on the line *x x* of Fig. 1.

Similar numerals of reference designate like and corresponding parts in the several figures of the drawings.

The device comprises a flexible casing 10, which is preferably composed of leather, and comprises two sections—a backing-strip 11 and facing-strip 12—the two being joined together at their edges preferably by a line of stitching. The casing 10 is widened at its central portion and the facing 12 is provided with a mirror-opening 13. A mirror-backing 14 is secured, preferably by stitching, to the facing-strip 12 around the opening 13, leaving a retaining-rim 15. This forms a suitable pocket 40 for the mirror 16, which fits snugly therein and is held in place by the retaining-rim 15.

Extending through the entire length of the flexible casing 10 is a flat metal retaining-spring 17, which preferably is loosely mounted therein and is arranged to extend across the back of the mirror-pocket. This spring may be placed in position when the casing is constructed, but for the purpose of having it removable an opening 18 is provided near 50 the end of the backing-strip 11, through which the spring may be introduced or removed, as desired.

As shown in Figs. 1 and 2, the device is inserted in the hat with ends engaging on opposite sides between the sweat-band and the inner wall. On account of the flat spring the device will conform substantially to the inner wall of the hat, and the opposite edges of the rim 15 will be caused to more firmly grip the edges of the mirror, and thereby securely hold it in place. As all the metal parts are completely incased there is no liability of the hat being injured, and the device can be applied to or removed from the same, as desired.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having now fully described the invention, what I claim as new, and desire to secure by Letters Patent, is—

1. A mirror-holder, comprising a flexible casing having a pocket open at its outer side and closed at the back, a mirror held within said pocket and exposed through the open side thereof, and a flat spring housed within said casing and extending from end to end thereof, said spring being arranged to extend across and bear against the closed back of the pocket, substantially as described.

2. A mirror-holder, comprising two strips of flexible material secured together along their edges, forming a casing, one of said strips being provided with an opening, a backing arranged behind the opening and secured to the strip having said opening, whereby a pocket is formed, a mirror arranged within said pocket, and a spring housed within said casing and extending across the back of the pocket, substantially as described.

In testimony that I claim the foregoing as my own I have hereto affixed my signature in the presence of two witnesses.

LEO WEISENBURGER.
